EXCAVATOR

Elmer T. Humphrey, Big Sandy, Mont.

Application February 26, 1940, Serial No. 320,813

16 Claims. (Cl. 37—104)

This invention relates to an excavator for cleaning out a groove or bed beneath a railroad track and facilitating the replacement of ties therein. When a worn or broken tie is removed from the track its bed is invariably disturbed and is unsuitable, without cleaning and refashioning, for receiving the new tie. Hitherto this operation has been carried out by hand tools and, what with the necessary removal of considerable ballast at the side or shoulder of the roadbed for the clearance of the tie as it is moved endwise to place, the operation has been a laborious and time consuming one.

It is the primary object of my invention, therefore, to provide a machine by which the necessary groove or trough and end clearance in the ballast for receiving the new tie may be rapidly and cleanly formed. Another object is to provide a machine of this kind which in addition to its function of excavating the bed for the tie, also may be used effectively to pull the new tie into place when the bed is completed, thus further facilitating the general operation of tie replacement.

A further object is to provide a machine for this purpose which may be movably supported upon the track and with means for readily adjusting the excavating mechanism according to the depth of groove or trough required for the tie.

Still another object of the invention is to provide in a machine of this kind, which includes as the excavator per se an endless chain member which necessarily encircles the rails, an improved means for quickly parting the chain and casting the ends aside onto the ground clear of the rails so that the machine may be quickly removed from the track when a train approaches.

These and other more detailed and specific objects will be disclosed in the course of the following specification, reference being had to the accompanying drawings, in which—

Fig. 1 is a plan view of my machine showing the same on a railroad track in position for the operation of scraping or excavating out a groove for a tie.

Fig. 2 is a vertical cross section along the line 2—2 in Fig. 1, this view also indicating in dotted lines the manner in which the chain when separated may be thrown aside clear of the track.

Fig. 3 is an enlarged side elevation showing adjacent end portions of the chain with a quickly releasable hook connection therefor.

Fig. 4 is a plan view of a portion of chain hav-

ing a knock out pin for disconnecting the chain at this point.

Fig. 5 is a view of the knock out pin alone.

Fig. 6 is a fragmentary view similar to the extreme lower right hand portion of Fig. 2 showing a tie being pulled into place beneath the rails.

Fig. 7 is an enlarged, fragmentary longitudinal section substantially along the line 7—7 in Fig. 1.

Fig. 8 is a somewhat diagrammatical perspective view of the release mechanism for throwing out the separated ends of the chain.

Fig. 9 is an enlarged plan view, with certain upright parts in cross section, of one end portion of the chain showing driving means and vertical adjustment means therefor.

Fig. 10 is an enlarged side elevation of the chain driving, supporting, and adjusting structure, with certain parts in section.

Referring now more particularly and by reference numerals to the drawings, my invention is seen to comprise a frame or car 11 which is carried by wheels 12 upon the rails A of the track, 25 said rails being as usual supported by ties B upon the ballast or roadbed C. The car may be propelled by hand, of course, but preferably is power driven by an engine or power unit D of conventional form and connected to the wheels by any 30 conventional driving mechanism (not shown).

The car frame 11 is generally rectangular in shape as shown and from medial points of the sides 13 thereof substantially U-shaped brackets or arms 14 are rigidly mounted and extended 35 outwardly or laterally. A pair of these brackets is provided at each side and at their outer ends they rigidly support the spaced, generally upright guide members 15 having channels opening inwardly toward each other, as shown.

40 Mounted between each pair of the guide members 15 is a carrier frame designated generally at 16 and having spaced sides 17 which nicely and slidably engage the channels of the guide members to slide up and down therein. Upper 45 and lower sprockets 18 and 19 are journaled and supported at upper and lower ends of the carrier frames 16 and over these sprockets is trained the conveyor or scraper mechanism designated generally at 20 and made up as here shown of a 50 chain 21 carrying suitable scrapers or tools 22. The length (vertically) of the frames 16 is such that the lower reach or portion of the chain 21 may pass transversely beneath the rails A while the upper reach may stand clear above the car frame 11 and the up and down movement of the

frames in the brackets 14 will of course raise and lower the chain relative to the ballast C.

The respective carrier frames 16 at each side of the car are connected by cross bars 23 to move upwardly and downwardly as a unit, and for thus operating the structure I provide one member 17 at each side with a toothed rack 24 and the adjacent guide members 15 carry bearings 25 in which is journaled a transversely extending shaft 26 carrying at its ends the gears 27 which mesh with the racks through suitable openings 28 in the guide members. It is evident that rotation of the shaft 26 will then raise and lower the carrier frames and the scraper mechanism 20 as a unit.

The shaft 26 may of course be turned by hand for making depth adjustments of the scraper mechanism, but preferably power actuated mechanism as I show herein is used for this purpose. The power unit D has the usual transmission mechanism E embodying a clutch and a reverse gear train separately actuatable by operating arms F and G. A cross panel 29 is supported by end brackets 30 above the car 11, and mounted on this panel are a clutch lever 31 and reverse lever 32 which are connected by link rods 33 and 34 to the respective arms F and G. These levers are thus convenient to hand of the operator seated on the seat 35, and he may control the travel of the car as may be desired.

A power take-off shaft 36 is extended from the transmission unit E and at its end enters a gear housing 37 wherein it carries a beveled gear 38. Oppositely faced beveled gears 39 and 40 are carried on a sleeve in the housing 37 and keyed on an upright drive shaft 41 which, at its upper end, enters a housing 42 and carries a worm 43 meshing with a worm gear 44 on the shaft 26. A fork 45 engages the sleeve of the gears 39 and 40 and a hand lever 46 on the panel 29 is connected by a link rod 47 and angular crank 48 to this fork. It is thus possible, by actuating the hand lever 46, to shift the gears 39 and 40 into selective engagement with drive gear 38 and reverse the direction at which the drive shaft 41 is turned by the power unit. The motion of this shaft is transmitted through gears 43 and 44 to the shaft 26 to raise and lower the scraping mechanism 20 accordingly, and of course an intermediate positioning of the hand lever will entirely disengage the reversing gears to maintain the selected adjustment.

The chain 21 is driven by mechanism now to be described. The upper chain sprockets 18 carry at one end the beveled gears 49 and the adjacent ends of one cross bar 23 carry bearings 50 in which is journaled a transversely extended drive shaft 51 with beveled pinions 52 at its ends to mesh with said gears 49. The shaft 51 is actually made in two coaxial end sections 51a and 51b which at their adjacent ends enter a housing 53, carried by the adjacent cross bar 23, and are provided within said housing with spaced, oppositely faced beveled gears 54 and 55. A drive pinion 56 is journaled and slidably mounted through a bearing 57 in the housing 53 on an axis substantially at right angles to the drive shaft 51 and outwardly carries a beveled gear 58. A power take-off shaft 59 from the transmission E has an upwardly extensible, keyed and telescopically connected extension section 60 which enters bearings 61 on the end of the housing 53 and carries a beveled gear 62 meshing with the gear 58. This assembly and mechanism

is such that the power transmitted through the shaft 59 and extension 60 will, through meshing of the gears 62, 58, 56, and 54—55, drive the shaft sections 51a and 51b in opposite directions. The 5 sprockets 18 will thus be properly rotated to cause the chain to travel around the sprockets and beneath the track. The telescopic connection at 59—60 permits the necessary vertical movement as the chain is raised and lowered.

10 For reversing the direction of travel of the chain the reverse lever 32 may be operated to control the direction of movement of the power take-off shaft 59, and in this operation the clutch lever 31 may of course be disengaged to prevent 15 travel movement of the car. The shaft 59 is thus driven at all times whether the car is moving or not, and to separately disengage the chain drive mechanism I employ a hand lever 63 mounted on the panel 29 and connected by a 20 link rod 64 to a shifting fork 65 which engages a sleeve 66 slidably carrying the drive pinion 56. By manipulating this lever the pinion 56 may be shifted to engage or disengage the gears 54 and 55 at will.

25 The chain 21 must obviously be retained in a taut condition while in operation, and for this purpose I prefer to employ a hydraulic or pneumatic jack device 67 which is supported upon a medial portion of the cross bars 23 and carries 30 at its extensible end a journaled roller 68. The actuating lever 69 of the jack is extended out over the panel 29 and by manipulating the lever the roller 68 may be readily forced up beneath the upper span of the chain to tighten the same 35 to the required extent as shown in Fig. 2. The jack may also be quickly collapsed or lowered by the conventional release mechanism.

The lower chain sprockets 19 are carried directly by the side members 17 in bearings 70 (Fig. 10) thereon, but the upper sprockets 18 are mounted between the forked arms 71 of throw-out levers 72. These levers 72 are pivotally mounted at lower ends 73 upon cross pins 74 extended between the side members 17 and normally the levers stand in upright position as shown with the forked arms 71 lying between upper ends of the side members and the sprocket drive gears 49 properly meshed with the pinions 52. However, the levers may swing outwardly 45 in vertical, transverse planes and torsional springs 75, coiled around the pins 74, are engaged at their ends at 76 with the levers to urge the same outward in this direction.

The chain 21 as here shown is a wide, heavy 55 duty type and the scrapers 22 are secured thereto in any suitable manner. The chain obviously must be capable of being parted, both for initially feeding it beneath the track and removing it therefrom, and to clear the track so that the car may be removed when a train approaches. For this purpose the chain at three or more points, designated at 77 in Fig. 2, has hooked links 78, shown in Fig. 3, to releasably engage the pins 79 of the adjacent links so that the 60 chain may be quickly disconnected at any of these points. The release points are all evenly spaced apart so that under any condition one will appear or be at the exposed upper span of the chain for most convenient manipulation. In lieu of the hooked link released, knock-out pins 80 may be provided in the chain and provided with well known types of retaining latches 81 which, when swung aside, permit the pins to be readily removed. This assembly is shown in Figs. 4 and 5.

When the chain is parted or disconnected at any of these release points 77, of course as they appear in the span between the upper sprockets 18, the parted ends of the chain may be thrown outwardly clear of the car and they will fall to the roadway alongside the track. The chain ends are actually forcefully thrown or cast outward by the levers 72 which, when freed by parting of the chain, will be swung outwardly by action of the springs 75 for this purpose. This operation is indicated by the dotted lines in Fig. 2.

Such forceful casting aside of the chain ends is not required except in the case of emergency or when a train approaches, and the levers 72 are accordingly normally retained in their upright inoperative positions by latches 82 pivotally mounted on cross members 83 extended between the side members 17 inwardly of the levers and which are urged to locking engagement by springs 84. A release lever 85 is connected to a short rock shaft 86 carried in bearings beneath the panel 29 and an arm 87 on the shaft is connected to cables 88 which run outwardly around pulleys 89 to points of connection at 90 with the latches. It is thus possible by actuating the lever 85 to pull both latches 82 clear of the levers 72 so that they may swing outward simultaneously when such action is desired. In reconnecting the chain the levers are first swung back by hand to upright positions, and as they come to a stop against the cross members 83 the latches 82 will automatically reengage and latch the levers in position. The chain may then again be connected. The chain drive gears 49 and 52 are of course remeshed when the levers are swung back to position.

Under some circumstances it may be desirable to prevent the parted ends of the chain from falling to the ground, and for this reason I provide tables 91 which are pivotally mounted by short extension arms 92 in bearings 93 on one member 15 at each side of the car so that, while normally carried clear of the chain as shown in Fig. 1, they may be swung outwardly in the horizontal to stand in position to receive and support the chain ends as one is shown to the right and in dotted lines in the same view.

It is of course necessary that the lower, working span of the chain beneath the track be caused to operate in a straight line as nearly as possible, and to this end I provide a hold down frame 94 which is secured by outwardly and upwardly inclined arms 95 to the side members 17 and by upwardly converging arms 96 to the cross bars 23 to thus move upwardly and downwardly as the chain is adjusted to depth. Rollers 97 are carried in spaced relation by this frame and bear downwardly upon the chain inwardly of the track rails A to prevent upward displacement of the chain as will be evident.

In operation the car may be run over the track to the point where a tie has been removed and it is desired to scrape out a groove or trough for the reception of a new tie. Here the car is stopped and one end of the chain is threaded or fed beneath the track until the ends of the chain may be properly connected and the chain meshed with its sprockets. In this connection it will be noted that the scrapers 22 are provided only over about half the overall length of the chain, and thus a sufficient portion of the chain to be fed first beneath the track is clear of scrapers which might interfere with this op-

eration. This is important from the convenience standpoint, as will be evident.

After connection of the chain as described, the jack 67 is extended to draw the chain taut and the control lever 63 is operated to engage the drive gears 54—55 and 56 and set the chain in motion. The direction of travel of the chain may be reversed and controlled by lever 32 as described, and the scrapers 22 will thus be carried by the chain beneath the track to engage the ballast C and clear out a clean groove or trough therein as will be understood. The depth of the trough may be controlled by progressively lowering the chain under control of the lever 46 as has been described.

When the trough has been completed the jack 67 is collapsed to loosen the chain and it is parted at any of the points 77 for removal from beneath the track. The new tie may be pulled endwise into place as the chain is being removed, as shown in Fig. 6, the end of the chain being connected for this purpose to gripping tongs 98 which engage the tie. The chain may be retained in engagement with one drive sprocket, during this operation, and the tie will be pulled easily beneath the rails into its prepared position.

The scrapers 22 may be of any desired form and shape and are here shown as made up of alternating slightly bent blades or spades 99 and marginally toothed grousers 100. These scrapers of course are effective when pulled by the chain in either direction.

It is thought that further details and advantageous features of the operation of my invention will be understood without additional description herein.

It is understood that suitable modifications may be made in the structure as disclosed, provided such modifications come within the spirit and scope of the appended claims. Having now therefore fully illustrated and described my invention, what I claim to be new and desire to protect by Letters Patent is:

1. A machine for clearing out a transverse trough beneath railway rails for the reception of a tie therein, comprising a frame supported over the rails, a chain extending over the frame and downwardly beneath the rails for transverse movement with respect to said rails, scraping tools carried by the chain, means for operating the chain, means for parting the chain, and means for forcefully casting the parted ends of the chain outwardly alongside the rails.

2. A machine for clearing out a transverse trough beneath railway rails for the reception of a tie therein, comprising a frame supported over the rails, a normally endless chain supported transversely over the frame and extending at a lower span beneath the rails, scraping tools carried by the chain, means for actuating the chain to progressively carry the tools beneath the rails in a crosswise direction and scrape out a trough in the ballast, means for parting the chain at some point in the portion over the frame, and means for mechanically throwing the upper parted ends of the chain outwardly clear of the rails.

3. A machine for clearing out a transverse trough beneath railway rails for the reception of a tie therein, comprising a frame supported over the rails, a normally endless chain supported transversely over the frame and extending at a lower span beneath the rails, scraping tools carried by the chain, means for actuating the chain to progressively carry the tools beneath

the rails in a crosswise direction and scrape out a trough in the ballast, means for parting the chain for removal from the rails, and means for connection to one end of the parted chain and engagement with a tie to drag the tie endwise into the prepared trough.

4. A machine for scraping a trough beneath railway rails for the reception of a tie, comprising a wheeled frame for travel movement on the rails, bracket arms extending outwardly from the frame, carrier frames slidably mounted for up and down movement with respect to the bracket arms in planes outwardly of the rails, sprockets carried at upper and lower ends of the carrier frames, a chain trained over the sprockets and passing at a lower portion crosswise beneath the rails, scraping tools carried by the chain, a power unit carried by the frame and operative to cause travel movement thereof, separate clutch and reversing means for controlling the travel movement, and power actuated mechanism responsive to said reversing means but independent of the clutch for moving the chain over the sprockets in either of two directions.

5. A machine for scraping a trough beneath railway rails for the reception of a tie, comprising a wheeled frame for travel movement on the rails, bracket arms extending outwardly from the frame, carrier frames slidably mounted for up and down movement with respect to the bracket arms in planes outwardly of the rails, sprockets carried at upper and lower ends of the carrier frames, a chain trained over the sprockets and passing at a lower portion crosswise beneath the rails, scraping tools carried by the chain, a power unit carried by the frame and operative to cause travel movement thereof, separate clutch and reversing means for controlling the travel movement, power actuated mechanism responsive to said reversing means but independent of the clutch for moving the chain over the sprockets in either of two directions, and separate means for disengaging said power actuated mechanism from the power unit.

6. A machine for scraping out a trough beneath railway rails to receive a tie, comprising a frame adapted to be supported over the rails, carrier frames supported from the frame at the sides thereof in generally upright planes outwardly of the rails, sprockets carried at upper and lower portions of the carrier frames, a chain trained over the sprockets and at a lower span passed beneath the rails, trough forming means on the chain, gears secured to the upper sprockets at each side of the frame, a drive shaft having independent sections journaled transversely on the frame, pinions at the ends of the shaft for driving the said gears and sprockets, and means for driving the shaft sections in opposite directions.

7. A machine for scraping out a trough beneath railway rails to receive a tie, comprising a frame adapted to be supported over the rails, carrier frames supported from the frame at the sides thereof in generally upright planes outwardly of the rails, sprockets carried at upper and lower portions of the carrier frames, a chain trained over the sprockets and at a lower span passed beneath the rails, trough forming means on the chain, gears secured to the upper sprockets at each side of the frame, a drive shaft having independent sections journaled transversely on the frame, pinions at the ends of the shaft for driving the said gears and sprockets, gears at inner

ends of the shaft sections, and a power driven reversible gear movable into and out of engagement with the said inner gears for driving the shaft sections in opposite directions.

5 8. A machine for scraping out a trough beneath railway rails to receive a tie, comprising a frame adapted to be supported over the rails, carrier frames supported from the frame at the sides thereof in generally upright planes outwardly of the rails, sprockets carried at upper and lower portions of the carrier frames, a chain trained over the sprockets and at a lower span passed beneath the rails, scraping tools carried by the chain, driving means engaging the upper sprockets for actuating the chain to move the scraping tools crosswise beneath the rails, and the said upper sprockets being movable outwardly out of engagement with their driving means.

20 9. A device for scraping out the ballast beneath a railway track to receive a tie, comprising a frame adapted to be supported above the track, frame members supported at the sides of the frame outwardly of the track, upper and lower sprockets mounted in the frame members, a chain trained around the sprockets for movement thereon transversely with respect to the track, ballast working tools carried by the chain, driving means for the upper sprockets, levers pivotally connected to the frame members and supporting the upper sprockets, and the said levers being spring set to swing outwardly and carry the sprockets out of engagement with their driving means.

25 10. A device for scraping out the ballast beneath a railway track to receive a tie, comprising a frame adapted to be supported above the track, frame members supported at the sides of the frame outwardly of the track, upper and lower sprockets mounted in the frame members, a chain trained around the sprockets for movement thereon transversely with respect to the track, ballast working tools carried by the chain, driving means for the upper sprockets, levers pivotally connected to the frame members and supporting the upper sprockets, the said levers being spring set to swing outwardly and carry the sprockets out of engagement with their driving means, releasable latch means for normally holding the levers against such movement, and means for releasing the levers from the latch means.

30 11. A machine for forming a bed beneath a railway track for the reception of a tie, comprising a supporting frame arranged over the track, bracket arms extended outwardly from the frame, carrier frames supported at outer ends of the arms for up and down movement in planes located outward of the track, sprockets carried by the carrier frames, a chain passed around the sprockets for movement transversely at one portion beneath the track, scraping tools carried by the chain, gear toothed racks on one side of the carrier frames, a shaft journaled transversely on the supporting frame, gears on the ends of the shaft meshing with the racks, a power unit on the supporting frame, means actuated by said power unit for rotating the shaft to thereby raise and lower the chain, means actuated by the power unit for driving the chain around the sprockets, and the said chain driving means including a vertically extensible and adjustable connection to permit up and down adjustment of the chain as it is driven.

35 12. A machine for clearing out a transverse

trough beneath a railway track to receive a tie therein, comprising a frame supported above the track, a normally endless chain supported by the frame around the track for transverse movement with respect thereto, scraping tools carried by the chain, means for parting the chain whereby upper parted ends thereof may be thrown aside, and table members movable to positions to receive and support the ends of the chain as they are thrown aside from the frame.

13. A machine for clearing out a transverse trough beneath railway rails for the reception of a tie therein, comprising a frame supported over the rails, a chain extending over the frame and downwardly beneath the rails for transverse movement with respect to said rails, scraping tools carried by the chain, means for parting the chain on the portion extending over the frame, a jack device engaging the chain to tighten the same, and the said jack device being releasable to thereby loosen the chain to permit it to be parted and its ends cast aside.

14. A machine for clearing out a transversely extending tie bed beneath a railroad track, comprising a frame, a chain supported by and over said frame and passing at a lower reach beneath the track, tools carried by the chain, means for parting the chain whereby end portions may be thrown outward from the frame, and table members movably supported from the frame at its sides to normally stand alongside the same clear of the chain but movable to positions in which they may receive and support the ends of the chain.

15. A machine for clearing out a trough beneath a railroad track for the reception of a

tie, comprising a main frame supported above the track, a chain supported over the main frame and passing at a lower reach transversely beneath the track, tools on the chain, carrier frames supported at the sides of the main frame for up and down movements with respect thereto, means on said carrier frames for supporting the end portions of the chain, cross members connecting said carrier frames, a center frame for restraining the said lower reach of the chain against upward movement, and a supporting structure for the said center frame including outwardly extending arms secured to the carrier frames and upwardly extending arms secured to said cross members.

16. A machine for clearing out a trough beneath a railroad track for the reception of a tie, comprising a main frame supported above the track, a chain supported over the main frame and passing at a lower reach transversely beneath the track, tools on the chain, carrier frames supported at the sides of the main frame for up and down movements with respect thereto, means on said carrier frames for supporting the end portions of the chain, cross members connecting said carrier frames, a center frame for restraining the said lower reach of the chain against upward movement, and a supporting structure for the said center frame including outwardly extending arms secured to the carrier frames and upwardly extending arms secured to said cross members.

17. A machine for clearing out a trough beneath a railroad track for the reception of a tie, comprising a main frame supported above the track, a chain supported over the main frame and passing at a lower reach transversely beneath the track, tools on the chain, carrier frames supported at the sides of the main frame for up and down movements with respect thereto, means on said carrier frames for supporting the end portions of the chain, cross members connecting said carrier frames, a center frame for restraining the said lower reach of the chain against upward movement, and a supporting structure for the said center frame including outwardly extending arms secured to the carrier frames and upwardly extending arms secured to said cross members, the said outwardly extending arms angling upwardly from the center frame to clear the track.

ELMER T. HUMPHREY.
